DESIGN FOR A SERVICE CABINET FOR PHONOGRAPHIC RECORDS

Alex Levine, Passaic, N. J.

Application June 28, 1946, Serial No. 131,147

Term of patent 7 years

(Cl. D80—11)

To all whom it may concern:

Be it known that I, Alex Levine, a citizen of the United States, residing at Passaic, in the county of Passaic and State of New Jersey, have invented a new, original, and ornamental Design for a Service Cabinet for Phonographic Records, of which the following is a specification, reference being had to the accompanying drawing, forming part thereof.

The drawing is a perspective view of a service cabinet for phonographic records showing my new design.

I claim:

The ornamental design for a service cabinet for phonographic records, substantially as shown.

ALEX LEVINE.
